(57) **CLAIM**

The ornamental design for a whole mouth floss device as shown and described.

DESCRIPTION

FIG. 1 is a perspective view of a whole mouth floss device showing the new design in a closed configuration, FIG. 2 is an exploded view of the whole mouth floss device, FIG. 3 is a top view of the whole mouth floss device in a closed configuration,

FIG. 4 is a front view thereof,

FIG. 5 is a right side view thereof, the left side view being a mirror image thereof,

FIG. 6 is a rear view thereof,

FIG. 7 is a cross-sectional view of the whole mouth floss device, taken along line 7-7 of FIG. 3,

FIG. 8 is a front view of the whole mouth floss device in an open configuration, the rear view being a mirror image thereof,

FIG. 9 is a top view thereof,

FIG. 10 is a right side view thereof, the left side view being a mirror image thereof,

FIG. 11 is a bottom view thereof; and,

FIG. 12 is a perspective view of the whole mouth floss device shown in an environment of use.

The broken lines showing a head and a face in FIG. 12 depict environment and form no part of the claimed design.

1 Claim, 7 Drawing Sheets
